UNITED STATES PATENT OFFICE.

LOUIS KING, OF ROCHESTER, NEW YORK.

DESIGN FOR A LAMP-CHIMNEY.

SPECIFICATION forming part of Design No. 22,139, dated January 17, 1893.

Application filed July 14, 1892. Serial No. 440,075. Term of patent 7 years.

To all whom it may concern:

Be it known that I, LOUIS KING, a citizen of the United States of America, residing at Rochester, in the county of Monroe and State 5 of New York, have invented and produced a new and original Design for Lamp-Chimneys, of which the following is a full, clear, and exact description, reference being had to the accompanying drawing, and to letters of reference marked thereon, which form a part of this specification.

In the drawing the figure represents a side view of a lamp chimney made in accordance with my design.

15 The lamp chimney is provided with a cylindrical base portion A, the upper edge of which is connected by a bead *a* to an outwardly extending circular plate B, which is slightly

curved as shown. Adjacent to the periphery of this plate is attached a truncated cone C, 20 which forms the body portion of the chimney, and to the upper end of this cone is a section D, which is flared outwardly in an ogee curve and has attached to its upper end a ring E with circular apertures *e*. The body of the 25 chimney has a rectangular panel as shown.

Having thus shown and described my design, what I claim is:

The design for a lamp chimney herein shown and described. 30

In testimony whereof I affix my signature in presence of two witnesses.

LOUIS KING.
